ATTORNEY

UNITED STATES PATENT OFFICE.

BERNARD KEISTER, OF CLEVELAND, OHIO.

ANTI-WINDOW-RATTLER.

1,294,915.

Specification of Letters Patent. Patented Feb. 18, 1919.

Application filed October 22, 1917. Serial No. 197,956.

To all whom it may concern:

Be it known that I, BERNARD KEISTER, a citizen of the United States, residing at Cleveland, in the county of Cuyahoga and State of Ohio, have invented certain new and useful Improvements in Anti-Window-Rattlers, of which the following is a specification.

This invention relates to sash holders and more particularly to a holding device which will prevent rattling of the sash within its frame.

The primary object of the invention is to provide an extremely simple and efficient device for holding a window sash against rattling, and to this end consists of a single piece of wire bent to form a plurality of spring arms, and adapted to be attached to the sash in such manner that the spring arms will engage the side walls of the groove in which the sash is arranged to slide and will thereby hold the sash against rattling.

Another object of the invention is to provide a device of this character which can be quickly and easily attached to any form of sliding sash without necessitating any modifications either in the sash or in the window frame in which it slides.

Other objects of the invention as well as its specific construction and the manner of attaching the same to a window frame will be more readily understood from the following description and accompanying drawings, in which drawings:—

Figure 1 is a fragmentary perspective view of a portion of a window frame and sash, showing the application of my invention.

Fig. 2 is a perspective view of the invention in attached position.

In the drawings wherein the invention is shown in its preferred embodiment, the numerals 1 designates generally one of the side bars of an ordinary window frame, 45 This side bar is provided with a groove 2 to receive in the usual manner one edge or side of the sliding sash 3, to the upper rail of the sash my invention is to be attached.

The sash holder or antirattler which forms the subject matter of this invention is clearly shown in Fig. 2 and is preferably formed of a single piece of wire possessing the desired amount of resiliency. In forming this device, the wire is first doubled upon itself as at 4 to provide the parallel sides 5 of an elongated loop designated generally by the

numeral 6. As shown the sides 5 of the loop are disposed in close proximity to one another and at a point remote from the point 4 each of the sides 5 is bent outwardly and slightly forwardly as at 7 and is then turned to extend upwardly substantially at right angles to the portion of the loop to provide the spring arms 8. These oppositely arranged arms 8 diverge slightly from one another and have their ends reversely curved to provide the terminal loops 9.

The device is attached to the upper corner of the sash as clearly shown in Fig. 1, the loop 6 resting upon the upper edge of the sash and being secured thereto by means of staples or like fastening means. The spring arms 8 are inclined forwardly to engage the bottom wall of the groove 2 and are adapted to press outwardly against the opposite walls of this groove with sufficient strength to hold the sash steady within said groove, thereby preventing the usual rattle.

It is to be understood that two of these devices are to be employed one being attached to each side of the upper rail of the sash and engaging each side of the window frame.

It is to be also understood that only a preferred embodiment of the invention has been shown and described and therefore I do not limit myself to the exact details of construction and arrangement set forth, but reserve the right to make such minor changes as may prove desirable and come within the scope of the appended claims.

I claim:—

1. The combination with a window sash and a side standard provided with a groove to receive one side of said sash, of an anti-rattling device comprising a single piece of wire bent to form a loop engageable with the upper rail of the sash, and a plurality of spring arms extending outwardly and upwardly from said loop for engagement with the bottom and side walls of said groove to retain the sash against rattling therein.

2. The combination with a window sash, and a supporting standard provided with a groove receiving one side of said sash, of an anti-rattling device comprising an elongated loop engaging the upper rail of the sash, spring arms extending outwardly and upwardly from said loop and loops formed on the extremities of said arms and engaging the bottom and side walls of the groove to prevent rattling of the sash therein.

3. The combination with a window sash of an anti-rattling device comprising a single piece of wire doubled upon itself to form an elongated loop adapted to be secured upon the upper rail of the sash, said loop including spaced side members having the free ends thereof turned outwardly and upwardly at an angle to said loop to provide oppositely disposed spring arms engageable with the side and bottom walls of the groove in

the window frame supporting said sash, said arms being inclined at an angle to the length of the loop to force the sash away from the bottom wall of the groove.

In testimony whereof I affix my signature 15
in presence of two witnesses.

BERNARD KEISTER.
